UNITED STATES PATENT OFFICE.

SIDNEY M. ISRAEL, OF RICHMOND HILL, NEW YORK.

DESIGN FOR A SEWER'S ELECTRIC-LIGHT STAND.

58,757.

Specification for Design.

Patented Aug. 30, 1921.

Application filed December 30, 1920. Serial No. 434,149. Term of patent 3½ years.

To all whom it may concern:

Be it known that I, SIDNEY M. ISRAEL, a citizen of the United States, residing at Richmond Hill, county of Queens, and State of New York, have invented a new, original, and ornamental design for Sewer's Electric-Light Stands, of which the following is a specification, reference being had to the accompanying drawing, forming part thereof.

The figure is a perspective view of a sewer's electric light stand, showing my new design.

I claim:

The ornamental design for a sewer's electric light stand, as shown.

SIDNEY M. ISRAEL.
